UNITED STATES PATENT OFFICE

HERBERT LEHMANN, OF NEW YORK, N. Y.

DESIGN FOR A FABRIC FOR SHOE UPPERS

Application filed January 20, 1932. Serial No. 42,567. Term of patent 3½ years.

To all whom it may concern:

Be it known that I, HERBERT LEHMANN, a citizen of the United States, residing at New York city, in the county and State of New York, have invented a new, original, and ornamental Design for Fabric for Shoe Uppers, of which the following is a specification, reference being had to the accompanying drawing, forming part thereof.

The figure is a plan view of a fabric for shoe uppers showing my new design, the dot and dash lines enclosing an area representing a repeat unit thereof.

I claim:

The ornamental design for a fabric for shoe uppers as shown and described.

HERBERT LEHMANN.
